(57) CLAIM

The ornamental design for a hockey net support plug pocket set as shown and described.

DESCRIPTION

FIG. 1 is a perspective top front right view of a hockey net support plug pocket set showing my new design;

FIG. 2 is a top plan view of the first flange feature of the hockey set support plug pocket set, shown separately for ease of illustration;

FIG. 3 is a front elevation view thereof, wherein a rear elevation view is an identical image thereof;

FIG. 4 is a bottom plan view thereof;

FIG. 5 is a right elevation view thereof, wherein a left elevation view is an identical image thereof;

FIG. 6 is a top plan view of the second flange feature of the hockey net support plug pocket set, shown separately for ease of illustration;

FIG. 7 is a front elevation view thereof, wherein a rear elevation view is an identical image thereof;

FIG. 8 is a bottom plan view thereof; and,

FIG. 9 is a right elevation view thereof, wherein a left elevation view is an identical image thereof.

The claim is directed to the collective appearance of the hockey net support plug pocket set shown in the figures. The components of the set are arranged on the drawing sheet for the convenience of illustration, and the position of the hockey net support plug pocket set forms no part of the claimed design.
